UNITED STATES PATENT OFFICE.

DAVID DIETRICH SMITH, OF CHICAGO, ILLINOIS.

DESIGN FOR A TOY MUSIC-BOX.

45,729.

Specification for Design.

Patented May 5, 1914.

Application filed August 9, 1913. Serial No. 783,958. Term of patent 3½ years.

To all whom it may concern:

Be it known that I, DAVID DIETRICH SMITH, a citizen of the United States, and a resident of the city of Chicago, in the county of Cook and State of Illinois, have invented a new, original, and ornamental Design for Toy Music-Boxes; and I do hereby declare that the following is a specification thereof, reference being had to the accompanying drawing, forming a part hereof, in which the figure is a perspective view of a toy music-box, showing my new design.

I claim:

The ornamental design of a toy music box as shown.

In testimony whereof I have hereunto set my hand in the presence of two subscribing witnesses.

DAVID DIETRICH SMITH.

In the presence of—

C. S. STARK,
F. T. LEBERSTEIN.
